UNITED STATES PATENT OFFICE.

FRANK JOSEPH LANDRY, OF AMHERST, NOVA SCOTIA, CANADA.

RAILWAY BAGGAGE-CAR AND THE LIKE.

1,231,916.

Specification of Letters Patent.

Patented July 3, 1917.

Application filed June 26, 1916. Serial No. 105,907.

To all whom it may concern:

Be it known that I, FRANK JOSEPH LANDRY, a subject of the King of Great Britain, and residing at 19 Havelock street, in the city of Amherst, Province of Nova Scotia, Dominion of Canada, have invented certain new and useful Improvements in Railway Baggage-Cars and the like, of which the following is a specification.

10 This invention relates to improvements in railway baggage cars. In the baggage cars at present in use in railway practice there is a great liability of water lodging on the door posts, and percolating under the floor of the car on to the sills, with result that the sill invariably rots both beneath the door posts and sometimes as deep as three feet into the center of the car, thereby necessitating the frequent renewal of the said sill, 15 a task involving considerable expense both in time, labor and material necessary to rebuild the car, and the principal objects of the present invention are to prevent the water coming in contact with the sill of the car either adjacent to the door posts or the foot-plate, and at the same time to provide for an adequate current of air being circulated under the foot plate so that there is no liability of any moisture lying therein. 20 Further objects are to permit of the drip plates used in this invention being utilized with equal effect on cars at present in use so that the expense of installing the device would be extremely low, to render the drip plates being interchangeable and of stock size, so that they may be readily used on different cars of the same type, and generally to adapt the several parts to better perform the functions required of them. 25

30 With the above and other objects in view, the invention consists essentially of the improved construction particularly described and set forth in the following specification and accompanying drawings forming part 40 of the same.

In the drawings,

Figure 1 is a fragmentary perspective view of a car sill and door-posts, with the foot-plate in position, and the cover plate 50 mounted on the front of the sill.

Fig. 2 is a fragmentary perspective view of the sill and door posts of a car with the foot plate and cover plate removed to show the location of the drip plates superimposed on the sill. 55

Fig. 3 is a fragmentary perspective view

of a door post with the metallic guard plates secured thereto.

Fig. 4 is a perspective view of a section of the drip plates. 60

Fig. 5 is a transverse section through the center of the door-way.

Fig. 6 is a transverse section through one of the door posts.

Like characters of reference refer to like 35 parts in the several figures.

Referring to the drawings, A represents a car sill, and B the door-posts mounted thereon, which door posts are provided at their lower end with curvilinear recesses 10 and 11 arranged in stepped relation, while the front and back faces of the door posts are provided with notches 12 and 13 the latter of which is formed with its upper edge beveled inwardly and upwardly as shown 75 at 14 in Figs. 2 and 6. Superimposed on the sill A, is a drip plate 15 of substantially Z-shaped in cross section, the outer flange 16 being designed to engage with the outer face of the sill A, while the inner flange 17 80 is upturned and designed to engage with the slot 18 extending transversely across the end of the flooring 19, the upper edge of which is recessed as shown at 20 for an object to be made clear hereafter. 85

The drip plates 15 are made in two sections, the adjacent ends of which are designed to form a lap joint while the opposite ends are provided with U-shaped flanges 21, having a recess 22 adjacent to the body 90 of the said drip plate, the said flange being adapted to engage with the recesses 10 and 11 in the door posts so that the outer face of the said door posts and the flange 21 are substantially flush. 95

It will be understood that in positioning these drip plates that they will be embedded in white lead against the door posts B and that the lap joint formed at the center of the said drip plates will be made water-tight 100 either by soldering or any other convenient means.

Lateral displacement of the drip plates 15 is eliminated by angle brackets 23 which are recessed on their inner face to engage with 105 the flange 16, the brackets being secured to the outer face of the sill by wood-screws or the like. Intermediate of the angle brackets 23 distance pieces 24 are positioned and suitably secured to the outer face of the 110 sill A, the inner faces of the distance pieces adjacent to the top thereof, being recessed

to engage with the flange 16. The foot plate 25 is superimposed on the drip plates 15, the ends of the foot plates being formed curvilinear to engage with the recess 22 formed in the U-shaped flanges 21 of the said drip plates, the rear edge of the foot plate being spaced from the drip plates by the distance piece 26 located therebetween. The foot plate 25 will preferably be formed of malleable iron and be secured to the angle brackets 23 by suitable bolts. The front of the sill A is now inclosed with the cover plate 27 the inner face of which engages with the distance pieces 24 so that the said cover plate is spaced from the front of the sill, and permitting an adequate ventilation taking place.

A metallic cover plate 28 is engaged with the recess 20 in the flooring 19, and bridges the joint between the said flooring and the foot plate 25, the said cover plate being provided with integral flanges or lugs 29 designed to engage with the notches 12 in the back of the door posts B, so facilitating in securing the said cover plate in position. This cover plate also carries a rail 30 suitably secured to the upper face and designed to act as a guide for the lower end of the door. Locking blocks 31 are engaged with the notches 13 in the front face of the door posts B, and frictionally engaged with the flange 21 of the drip plates 15 pressing the same tightly into contact with the said door posts, whereupon the metallic guard straps 32 are secured to the outer curvilinear face of the door posts to prevent the same from being damaged by any baggage impinging thereon.

The assembly of the device will be readily understood from the foregoing description. When a car fitted in the above described manner is in use, any water percolating be-

tween the foot plate 25 and the lower end of the door posts B will be collected on the metallic drip plates 15 and discharged over 45 the outer edge thereof on to the track, while the provision of an adequate ventilation of the drip plates will prevent any water from lying stagnant thereon.

While the applicant has found that to 50 form the drip plates 15 of copper gives good results, other metals may be used with equal satisfaction.

From the above description it will be seen that I have invented a device which can be 55 advantageously employed on railway freight cars, so that the sills and door posts may be adequately protected against damp rot.

As many changes could be made in the above construction, and many apparently 60 widely different embodiments of my invention, constructed within the scope of the claim, and without departing from the spirit or scope thereof, it is intended that all matter contained in the accompanying 65 specification and drawings be interpreted as illustrative, and not in a limiting sense.

What I claim as my invention is:

In a car the combination with the sill and door posts thereof, of a drip plate substantially Z-shaped in cross-section, having its outer flange engaging the outer face of the sill, flooring boards having transverse grooves engaging the inner flange of the drip plate, a foot plate located above the drip plate and spaced therefrom, and a cover plate bridging the joint of the foot plate and flooring.

In witness whereof I have hereunto set my hand in the presence of a witness.

FRANK JOSEPH LANDRY.

Witness:

JAMES MITCHELL.
